DESIGN FOR A COMPACT OR THE LIKE

Walter Zipper, Vienna, Austria

Application March 24, 1934, Serial No. 51,173

Term of patent 7 years

To all whom it may concern:

Be it known that I, WALTER ZIPPER, a citizen of Austria, residing at Vienna, Austria, have invented a new, original, and ornamental Design for Compacts or the like, of which the following is a specification, reference being had to the accompanying drawing, forming a part hereof.

Fig. 2 is a side view of the same.

Fig. 3 is a plan view of the same in open position.

I claim:

The ornamental design for a compact or the like as shown and described.

WALTER ZIPPER.
